(57) CLAIM

The ornamental design for a battery for a cellular phone, as shown and described.

DESCRIPTION

FIG. 1 is a left, top, front isometric view of a battery for a cellular phone showing our new design; FIG. 2 is a left, top, rear isometric view thereof; and FIG. 3 is a right side elevational view thereof; and FIG. 4 is a left side elevational view thereof; and FIG. 5 is a front elevational view thereof; and FIG. 6 is a rear elevational view thereof; and FIG. 7 is a bottom plan view thereof; and, FIG. 8 is a top plan view thereof.

The broken lines in FIGS. 2 and 6 are included for the purpose of illustrating a portion of the battery that forms no part of the claimed design.

1 Claim, 6 Drawing Sheets
